UNITED STATES PATENT OFFICE.

ALEXANDER CHURCHWARD, OF NEW YORK, N. Y., ASSIGNOR TO WILSON WELDER & METALS COMPANY, INC., A CORPORATION OF NEW YORK.

ELECTRICAL SOLENOID.

1,389,625.

Specification of Letters Patent. Patented Sept. 6, 1921.

Application filed June 24, 1919. Serial No. 306,373.

To all whom it may concern:

Be it known that I, ALEXANDER CHURCHWARD, a citizen of the United States, residing at New York city, county of New York, 5 and State of New York, have invented certain new and useful Improvements in Electrical Solenoids, of which the following is a specification.

This invention is an improvement in electrical solenoids, for instance such as employed in the current-regulating apparatus of an electric welding system; and the object of the invention is to increase the efficiency and reliability of the device.

15 One adaptation of the invention is illustrated in the accompanying drawings in which:

Figure 1 is a diagram of an electrical arc-welding system employing the invention;

Fig. 2 is a vertical midsection of a solenoid embodying the invention;

Fig. 3 is a perspective view of the upper core-spacing-and-lubricating ring; and

25 Fig. 4 is a perspective view of the lower core-spacing-and-lubricating ring.

In the illustrated adaptation of the invention, the solenoid coil 5 is included in the arc welding circuit in series with the 30 generator 6, the carbon-pile variable-resistance 7, and the welding electrodes 8. A lever 9 pivoted at 10 subjects the pile to compression under the lever-moment developed by the tension spring 11, while the solenoid

35 5 pulls on the lever in opposition to this spring, so that the resultant pile-compressing effort will always be proportionate to the preponderance of the spring effort over the solenoid effort. Thus as the resistance 40 of the welding arc varies, the consequent variations of current in the solenoid produce compensative variations in the pile resistance, all in accordance with principles and practice now established in the art.

45 In such use of a solenoid it is desirable to attain the highest electro-mechanical efficiency, and most sensitive responsiveness without sticking of the core; and my invention is directed to this purpose.

50 The solenoid coil 5 is wound on a non-magnetic metal spool 12, and surrounded by the usual magnetic casing 13 of the iron-clad type of solenoid. The casing has an upper annular iron pole-piece 14 and a lower

hollow cylindrical iron pole-piece 15, and 55 the entire solenoid is mounted on a suitable bracket 16. The hollow cylindrical core 17 is connected by a link 18 to the pile-compressing lever 9.

Upon, or in proximity to, the upper pole 60 of the solenoid, is mounted a bearing ring 19 of suitable non-magnetic self-lubricating anti-friction material, such as a mixture of Babbitt metal and fine graphite. This bearing ring may be secured as shown, by two 65 clamping rings 20 and 21, screwed to the annular pole-piece and the coil spool. The inside of this bearing ring is smoothly polished and has a sliding fit on the solenoid core 17 which is also smoothly polished and 70 slightly smaller than the bore of the solenoid spool, to afford a mechanical clearance. This bore of the solenoid spool may be also smoothly polished, and may have a sliding fit on another bearing ring 22 which may be 75 of the same material as the ring 19, and may be secured on the solenoid core at or near its lower end, for instance by being fitted over a reduced portion of the core end and secured by a nut 23.

The bearing rings 19 and 22 guide the solenoid core in its most efficient central position in the solenoid, and without sticking.

The invention may be embodied in different specific constructions, within its general principles and the scope of the following claims.

I claim:

1. A solenoid comprising a coil, a core 90 working therein, and a guide of self-lubricating anti-friction material secured in co-axial relation with the coil and fitting the core.

2. A solenoid comprising a coil, a tube 95 therein, a core working in the tube with a clearance space, and a guide of self-lubricating anti-friction material secured in co-axial relation to the tube and fitting the solenoid core.

3. A solenoid comprising a coil, a core working therein, and a guide of non-magnetic self-lubricating anti-friction material secured in co-axial relation with the coil and fitting the core.

4. A solenoid comprising a coil, a tube 105 therein, a core working in the tube with a clearance space, and a guide of non-magnetic

- self-lubricating anti-friction material secured in co-axial relation to the tube and fitting the solenoid core.
5. A solenoid comprising a coil, a tube therein, a core working in the tube with a clearance space, and a guide of non-magnetic self-lubricating anti-friction material connected with the tube in co-axial relation therewith and fitting the core.
- 10 6. A solenoid comprising an iron-clad coil with an annular pole-piece, a core working in the coil with a clearance, and a guide of non-magnetic self-lubricating anti-friction material secured on the pole-piece and fitting the core.
7. A solenoid comprising a coil, a non-magnetic metal tube therein, a core working in the tube with a clearance, and separating devices of self-lubricating anti-friction material arranged to maintain the clearance between the tube and core members and secured to each of said members and bearing on the other of said members.
